UNITED STATES PATENT OFFICE.

HOWARD H. JOHNSTON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL APPARATUS.

Original application filed May 23, 1919, Serial No. 299,183. Divided and this application filed September 2, 1922. Serial No. 535,872.

To all whom it may concern:

Be it known that I, HOWARD H. JOHNSTON, a citizen of the United States, and a resident of Edgewood Park, in the county of Allegheny and State of Pennsylvania, have invented a new and useful Improvement in Control Apparatus, of which the following is a specification, this application being a division of my copending application Serial No. 299,183, filed May 23, 1919, and assigned to the Westinghouse Electric & Manufacturing Company.

My invention relates to control apparatus, particularly for use in automatic control systems requiring protection by the familiar limit switch and overload trip device.

One object of my invention is to provide a single relay device having the double function of both a limit switch and an overload trip, the parts being so related that a single actuating coil may be utilized for independently performing the two functions, that is to say, under different operating conditions corresponding to the normal maximum, and to an overload current.

Another object of my invention is to provide a combined relay device of the above-indicated character having a plurality of actuating coils so connected to the load-circuit to be controlled as to effect similar actuations of the device during the occurrence of a predetermined load-circuit current or of a substantial doubling thereof; or, in other words, I provide a single relay device for affording the same limit-switch operation during the series-parallel connections of a plurality of electric motors, for example, and also the same degree of overload protection during both series and parallel operation of the motors.

Other specific objects of my invention will become evident from the following detailed description, taken in conjunction with the accompanying drawing, wherein Figure 1 is a view in elevation of a combined relay device constructed in accordance with the present invention; Fig. 2 is a diagrammatic view of a series-parallel system of control embodying the relay device that is shown in Fig. 1; and Fig. 3 is a chart representing various flux values during different operating conditions of the relay device.

Referring to Fig. 1, the structure shown comprises a series or current coil 1; a shunt

or voltage coil 2 alined therewith; concentrically related stationary and movable core members 3 and 4, respectively; a plurality of movable contact members or discs 5 and 6, respectively corresponding to the limit-switch and to the overload-trip functions of the device, both of the contact discs being loosely mounted upon a centrally-located rod or core member 7 that extends through both the movable and the stationary core members 3 and 4, respectively; and a movable armature device 8 for a purpose to be set forth.

The series coil 1 comprises a plurality of convolutions of strap conductor of suitable current-carrying capacity, while the shunt coil 2 may be formed of relatively small cross-section wire, since only a relatively low current passes therethrough.

The stationary core member 3 is located substantially within the series coil 1, while the movable core member or plunger 4 is substantially surrounded by the shunt coil 2 a suitable length of air-gap being left between the two core members, in accordance with a familiar practice. Also, a suitable spring 4a, located in the air-gap, serves to bias the plunger 4 to the illustrated upper position.

The contact disc 5 is resiliently associated with the concentrically-related rod 7 and movable core 4 by means of a coil or compression spring 12, one end of which engages the upper face of the core, the spring acting to force the disc 5 upwardly towards the illustrated position, and also towards a position of electrical contact with a set of stationary terminals 14 and 15, which are connected in the customary circuit that is controlled by a limit switch or current relay in automatic control systems for railway motors, and the like. A centering member 12a moves with the plunger 4 to limit the upward travel thereof.

The contact disc 6, corresponding to the overload-trip function of the relay device, is likewise resiliently associated with the rod 7 through the agency of a helical spring 16, the upper end of which bears against a pin 17 in the rod 7 to bias the contact disk downwardly towards a position of engagement with another pin 18 and also towards a position of electrical contact with a plurality of stationary contact terminals

19 and 20, which are connected in circuit in accordance with the familiar practice relative to overload-trip devices.

As previously stated, the rod 7 extends through both the stationary and the movable core members 3 and 4 respectively, being journaled at its upper end in a suitable strap or bracket 21, the lower end of the rod projecting slightly below the stationary core member 3 and resting upon an oscillatable armature or magnetizable member 22, one end of which is pivotally mounted upon a suitable pin 23. The entire armature device 8, including the armature proper 22 and a latch or detent 24, is preferably of the well-known form that is customarily associated with overload-trip relay devices. See, for example, Patent No. 1,312,757, granted August 12, 1919. Without complete illustration, it will be understood that the latch 24 normally holds the armature 22 in the illustrated position and is itself biased downwardly to prevent the return of the armature 22 to the illustrated position after it has been attracted upwardly by the core members to its overload position. Preferably, the familiar electrically-controlled resetting device is also associated with the latch 24 to return the latch and the armature to the illustrated position whenever the motorman throws a controlling switch. Since the resetting feature is well-known in the art, and, moreover, is not essential to the operation of my present invention, I have not deemed it necessary to completely illustrate this device.

The mechanical operation of my combined relay device may be set forth as follows: Assuming first that the series coil 1 alone is energized, the movable core member 4 is attracted downwardly, to allow the contact disc 5 to drop from its position of engagement with the stationary contact terminals 14 and 15, whenever a predetermined value of current, corresponding to the desired normal maximum operating value in the load circuit, traverses the series coil 1. As soon as the current decreases to a certain value, the movable core or plunger 4 is returned by the spring 4a to its illustrated upper position to resiliently actuate the contact disc 5 to the position of engagement with the contact terminals 14 and 15. In this way, the familiar intermittent energization of the desired auxiliary governing circuits in an automatic system of control, corresponding to the well-known limit-switch or current-relay action, is provided by the illustrated relay device.

If the current in the series coil 1 attains an undesirably high or overload value, the armature 22 is attracted upwardly to a position of direct engagement with the lower face of the stationary core member 3 to carry the rod 7 upwardly to a sufficient extent to

lift the contact disc 6 out of engagement with the terminals 19 and 20. In this way, the customary governing circuit corresponding to overload-trip protection is opened at any desired main-circuit current value, dependent upon the adjustment of the armature device 8, as will be understood by those skilled in the art. During the overload operation just described, the limit-switch disc 5 is retained spaced from the contact terminals 14 and 15 by reason of the previously described action of the core 4.

Consequently, the limit-switch and overload-trip functions of the relay device are accomplished entirely independently of each other, and, moreover, employ different magnetizable members, viz, the movable core 4 and the armature 22, for effecting the desired results.

Referring to Fig. 2, the system shown is of a familiar type for controlling a plurality of railway motors and comprises, essentially, suitable supply-circuit conductors such as Trolley and Ground; a plurality of dynamo-electric machines, respectively having commutator-type-armatures A1 and A2 and series field windings F1 and F2; an accelerating resistor 30; and a plurality of switches: LS for governing the connection of the motors to the supply circuit, R1, R2 and R3 for short-circuiting different sections of the accelerating resistor 30, S corresponding to series connection of the motors and P and G corresponding to parallel relation of the motors.

My combined relay device is illustrated diagrammatically in Fig. 2, the series actuating coil 1 being continuously connected in series relation with the motor circuit to receive the full current thereof, while the shunt coil 2 is connected in a circuit that is established from the Trolley through conductor 31, interlock P-in of the parallel-connecting switch P, conductor 32, actuating coil 2, adjustable resistor 33, and thence to Ground. In other words, the series coil 1 registers the current flowing through the motor circuit, whereas the shunt coil 2 measures the voltage across the motor circuit.

Inasmuch as an auxiliary governing system for the various switches shown in Fig. 2 may be readily devised by those skilled in the art, in accordance with well-known operating principles, I have not deemed it necessary to illustrate or describe such an auxiliary system. Moreover, since the ordinary limit-switch and overload-trip functions are well-known and the connections of the separate relay devices that are normally employed for these two purposes are also familiar, I have not considered it necessary to illustrate in detail such connections of the contact discs 5 and 6, which, as previously stated, correspond in every way to the cus-

tomary limit-switch and overload-trip operations, respectively.

Assuming that it is desired to effect series operation of the illustrated motors, the switches LS and S are closed to establish a circuit from the Trolley through the series-actuating coil 1 of my relay device, line switch LS, the entire accelerating resistor 30, armature A1, field winding F1, switch S, 10 armature A2, and field winding F2 to Ground. Thus, the series actuating coil 1 receives the full current traversing the motors, whereas the shunt actuating coil 2 is deenergized by reason of the open condition 15 of the switch P and, therefore, of the circuit for the actuating coil.

It will be understood that the resistor short-circuiting switches R1, R2 and R3 may be successively closed, in accordance with 20 the operation of the actuating coil 1 and the contact disc 5 of my relay device, as previously set forth, to gradually short-circuit the accelerating resistor 30 and accelerate the motors to full series relation.

25 The familiar shunting transition of the motors, involving the closure of switch P, the opening of switch S and the closure of switch G, may then be effected to thereby connect the motors in parallel relation, as 30 will be evident without a detailed tracing of the circuits. Consequently, the combined current that traverses the two motors, equaling substantially twice the amount flowing through the motor circuit during series operation, 35 also traverses the series actuating coil 1 of my relay device. For this reason, the limit-switch setting of the relay device would be substantially doubled over that employed during series acceleration and de- 40 sired during parallel operation also, were it not for the additional provision that I make. However, by utilizing the shunt coil 2 during such parallel operation and connecting it differentially with respect to the 45 series-actuating coil 1, the same limit setting, and likewise the same degree of overload protection, is obtained during both series and parallel connection of the motors, irre- 50 spective of the substantially doubling of current in the series-actuating coil 1.

The energization of the shunt coil 2 is automatically effected upon the closure of the parallel-connecting switch P by reason of the formation of the previously traced 55 circuit through the coil 2 and the interlock P-in. By mechanically adjusting the armature 22 of the relay device in the usual manner, before the car is put into service, to provide the desired degree of overload protection, and by then manipulating the resistor 33 to a corresponding condition, the actuating coils 1 and 2 of the relay device, 60 by reason of their differential action, will provide the same degree of magnetic attraction or the same amount of effective flux

during both the series and the parallel operation of the motors.

This fact is graphically shown in Fig. 3, wherein the vector ϕ_1 corresponds to the average flux emitted by the series-actuating coil 1 during series operation of the motors, or, in other words, the vector ϕ_1 is a measure of the average magnetic attraction upon the movable core 4 of the relay device. A substantially equal value of flux is created by the series coil 1 during the transitional period, while an equal and opposite amount of flux, represented by the vector ϕ_2 is produced by the shunt coil 2 during the transition of the motors from series to parallel relation, before the parallel connection is actually completed.

The normal or average flux conditions in the relay device during such parallel operation are represented by the correspondingly designated vectors in Fig. 3, ϕ_3 representing the substantially doubled flux created in the series coil 1 by reason of the parallel connection of the motors, while ϕ_4 indicates the opposing or differential flux that is set up by the shunt coil 2. Consequently, the effective flux that acts upon the movable core member 4 is substantially equal to the flux ϕ_1 , which represents the total flux created by the relay device during series operation of the motors.

The next succeeding set of vectors in Fig. 3 shows a vector ϕ_4 , greater than the sum of the vectors ϕ_1 and ϕ_3 , to represent the increased total flux that is produced in the relay device whenever the limit-switch portion thereof functions to effect the operation of a resistor short-circuiting switch such as R1, which, of course, causes a temporary increase of current in the motor circuit. The vector ϕ_4 , therefore, corresponds to the value of current necessary to effect the previously-described limit-switch action of my relay device.

The next set of vectors in Fig. 3 includes a vector ϕ_5 , longer than the vector ϕ_4 , and corresponding to the amount of current that is required to traverse the series actuating coil 1 to cause the armature 22 to assume its upper position and thus lift the contact disc 6, whereby the desired overload protection of the motors is provided.

The last vector ϕ_6 corresponds to the effective flux produced by the relay device under overload conditions. As indicated by the accompanying legends, the vector ϕ_6 is equal to the sum of the vectors ϕ_2 and ϕ_5 , or to the difference of the vectors ϕ_5 and ϕ_3 , plus the vector ϕ_1 . Since the vectorial sum of ϕ_2 and ϕ_5 represents the effective magnetic attraction exerted by the relay device during parallel operation of the motors, while the vectorial difference of ϕ_5 and ϕ_3 , plus the vector ϕ_1 , represents that attraction during series connection of the motors, it fol-

lows that substantially the same degree of overload protection is automatically furnished by my relay device during both series and parallel operation. By analogy, it also follows that the same average current is maintained by the limit-switch action of my relay device under both conditions of motor operation.

I do not wish to be restricted to the specific structural details or arrangement of parts herein set forth, as various modification thereof may be effected without departing from the spirit and scope of my invention. I desire, therefore, that only such limitations shall be imposed as are indicated in the appended claims.

I claim as my invention:

1. In a switch, in combination, a plurality of contact members for controlling electric circuits, a movable contact carrier, said contact members being movably mounted on the carrier, electromagnetic means adapted to effect the movement of a contact member independently of the carrier, and means operated by said electromagnetic means disposed to actuate the carrier.

2. In a switch, in combination, a plurality of contact members for controlling electric circuits, a movable contact carrier, said contact members being movably mounted on the carrier, electromagnetic means adapted to effect the movement of a contact member independently of the carrier, means operated by said electromagnetic means disposed to actuate the carrier, and resilient means co-operative to urge the contact members to predetermined positions relative to the carrier.

3. In a switching device, the combination with a movable core member, of an actuating coil therefor, a rod extending through said core member, and a plurality of contact members mounted upon said rod and respectively actuatable by the core member and the rod.

4. In a switching device, the combination with a movable core member, of an actuating coil therefor, a rod extending through said core member, a plurality of sets of stationary contact terminals, and a plurality of contact members mounted upon said rod and respectively actuatable upwardly by the core and downwardly by the rod to engage the respective sets of contact terminals.

5. In a switching device, the combination with a movable core member, of an actuating coil therefor, a rod extending through said core member, a plurality of sets of stationary contact terminals, and a plurality of contact members resiliently mounted upon said rod and yieldingly actuatable upwardly by the core to engage one set of contact terminals and yieldingly actuatable down-

wardly by the rod to engage another set, respectively.

6. In a switching device, the combination with co-operating stationary and movable core members, of a plurality of actuating coils substantially enclosing the respective core members, a rod extending through the core members, a plurality of sets of stationary contact terminals, a plurality of contact discs resiliently mounted upon said rod one of which is yieldingly actuatable upwardly by the core to engage one set of contact terminals, and an armature attractable by said core members to actuate said rod and effect disengagement of a second contact disc from a second set of contact terminals.

7. In a switch, in combination, a movable contact-carrying member, a plurality of contact members movably disposed on said member, a core member operable to effect a movement of a contact member independently of the contact-carrying member, an actuating coil for the core member, and means actuated by the coil disposed to operate the contact-carrying member.

8. In a switch, in combination, a movable contact-carrying member, a plurality of contact members movably disposed on said member, a core member operable to effect a movement of a contact member independently of the contact-carrying member, an actuating coil for the core member, and means actuated by the coil disposed to operate the contact-carrying member, said core and contact-carrying member being disposed to move the contact members in opposite directions.

9. In a switching device, the combination with a movable core member, of an actuating coil therefor, a rod extending through said core member, a plurality of stationary contact terminals, and a plurality of contact members, respectively actuatable in opposite directions by said core member and said rod to engage the respective stationary contact terminals.

10. In a switch, in combination, a movable contact-carrying member, a plurality of contact members movably disposed on said member, a core operable to effect the actuation of a contact member independently of the contact-carrying member, resilient means co-operative with the core to urge the contact member to a predetermined position relative to the carrying member, an actuating coil for the core, and means energized by the coil to operate said carrying member.

In testimony whereof, I have hereunto subscribed my name this 30th day of August, 1922.

HOWARD H. JOHNSTON.
